Linus E. Russell, Springfield, Ohio, assignor to
Peters and Russell, Inc., Springfield, Ohio, a
corporation of Ohio

Application May 10, 1939, Serial No. 84,912

Term of patent 7 years

To all whom it may concern:

Be it known that I, Linus E. Russell, a citizen
of the United States, residing at Springfield, Clark
County, State of Ohio, have invented a new, orig-
inal, and ornamental Design for an Exhaust Pipe
Extension, of which the following is a specifica-
tion, reference being had to the accompanying
drawing, forming a part thereof, in which

Fig. 1 is a perspective view of an exhaust pipe
extension embodying the new design.

Fig. 2 is a top plan view,
Fig. 3 is a side elevational view, and
Fig. 4 is an end view thereof.

I claim:

The ornamental design for an exhaust pipe
extension, substantially as shown.

LINUS E. RUSSELL.
